C. F. Brown.
Bathometer

No 11,001.

Patented Jun. 6, 1854.

UNITED STATES PATENT OFFICE.

CHARLES F. BROWN, OF WARREN, RHODE ISLAND.

INSTRUMENT FOR TAKING DEEP-SEA SOUNDINGS.

Specification of Letters Patent No. 11,001, dated June 6, 1854.

To all whom it may concern:

Be it known that I, CHARLES F. BROWN, of Warren, in the county of Bristol and State of Rhode Island, have invented a new 5 and useful Improvement for Sounding or Ascertaining the Depth of the Ocean; and I do hereby declare that the following is a full, clear, and exact description of the construction and operation of the same, reference being had to the accompanying drawings forming part of this specification, in 10 which—

Figure 1, is an external view of the implement. Fig. 2, is a vertical section of the 15 lower portion of the implement, showing the mechanism by which the powder is fired. Fig. 3, is an external view of the extreme lower portion of the implement, designed to show more clearly the office of the clamps 20 and nut. Fig. 4, is a detached plan or top view of the clamps. Fig. 5, is a plan or top view of the tube which contains the needle, showing the collar, and slots in which the feathers on the needle head or 25 boss work.

Similar letters of reference indicate corresponding parts in each of the several figures.

This invention relates to a new and useful 30 implement for sounding or ascertaining the depth of the ocean, and consists in attaching to a spindle or shaft a chamber of a prolate spheroidal form, said chamber containing a requisite quantity of gun powder, 35 within the lower part of the spindle or shaft and underneath the spheroidal chamber there is placed a needle which is operated by a spring and forced against a cap placed on a nipple at the lower end of the chamber, 40 said needle being forced against the cap and firing the powder, when the lower end of the spindle strikes the bottom of the ocean, by means of suitable mechanism which will be presently described.

The implement is allowed to descend or 45 is let fall from the surface of the water, and the time which elapses from the moment the implement is let fall 'till the report is heard, or the concussion felt, is denoted by a stop watch. Reference is then 50 made to a table formed by previous experiments, and the correct depth ascertained—the depth being in proportion to the time which elapses from the letting fall of the

implement 'till the report is heard or the 55 concussion felt the increase of buoyancy from increased depth being taken into account.

To enable others skilled in the art to make 60 and use my invention I will proceed to describe its construction and operation.

A, represents a spindle or shaft having at 65 its upper end two spiral flanches a, a, see Fig. 1. To this spindle or shaft there is attached a metal chamber B, of a very prolate spheroidal form. This chamber is filled with a requisite quantity of gun powder.

The lower part of the spindle or shaft A, above the chamber B, is screwed into the upper part of the chamber at b, and is made 70 water tight by any suitable means. In the lower end of the chamber B, there is screwed a pintle C, having a nipple c, at its lower end as seen in Fig. 2. A hole or passage d, is made through the nipple and pintle; said 75 hole or passage communicating with the interior of the chamber B. The pintle C, is screwed water tight into the lower part of the chamber.

On the lower end of the pintle C, there is 80 a screw thread on which the upper end of a tube D, is screwed see Fig. 2; the tube D, being about the same diameter as the shaft or spindle A, above the chamber, and forming, in effect, when secured on the pintle C, 85 a part of the shaft A. This tube D, has within it a needle E, on the upper part of which there is a head or boss e, having upon its surface at opposite points two longitudinal feathers f, f, which fit in slots g, g, in a 90 collar h, within the tube see Figs. 2, and 5. Underneath the head or boss e, and around the needle E, between the head or boss e, and the bottom i, of the tube there is a spiral spring j.

The lower part of the needle E, has a screw thread cut upon it and extends through an aperture in the bottom of the tube.

The lower end of the tube D, fits loosely 100 within a metal collar or socket F, on the outer lower part of which a screw thread is cut as shown in Figs. 1, 2, and 3; the collar or socket is also secured or fastened into a metal hub or cylinder G, having a vertical aperture k, through its center as shown in 105 Fig. 2.

On the lower outer part of the collar or socket F, where the screw thread is cut a

metal nut H works. The collar or socket F, has two triangular openings l, l, see Figs. 2, and 3, cut through its sides at opposite points, as shown in Figs. 1 and 2. On the 5 bottom of the collar or socket F, there are two vertical pins m, m, of triangular shape. These pins are placed about in the center of the openings l, one pin in each opening. A clamp or nut formed of two horizontal 10 plates n, n, is placed through the triangular openings l, l, as seen in Figs. 1, 2 and 3. The lower part of the needle passing through the plates n, n; a half round or circle having a female thread being cut in each plate and 15 forming a circular opening o, when the plates are in contact as shown in Fig. 4. The plates n, n, have a pin p, at each end said pins passing loosely through the plates and allowing them to be brought together 20 or forced apart, the pins keeping the plates in proper position.

Between the two plates are small apertures r, r, in which the tops of triangular pins m, m, fit when forcing the plates apart.

25 I will first proceed to describe the operation of the needle or the manner in which it is made to act upon the cap on the nipple c. The needle E, is depressed within the tube D, by turning the hub or cylinder G, or if 30 the tube D, is detached from the pinte C, by turning the tube, the turning of either effects the same object. The needle E, is prevented from turning within the tube D, by means of feathers f, f, fitting in the slots 35 g, g, in the collar h, and consequently the needle is forced downward, as its lower end passes through the plates n, n, which is in effect a nut, the plates being bound together as they are kept upward in the upper parts 40 of the triangular openings l, by the nut H, which is screwed up against them as shown in Fig. 1, and in Figs. 2 and 3. As the needle is depressed the spring j, is proportionally compressed, and when compressed 45 sufficiently, the tube D, is screwed on the pinte C, and the nut H, screwed downward from the plates n, n, to the position shown in black in Figs. 2 and 3. The plates n, n, are then of course free from the nut H, 50 and the hub or cylinder G, is prevented from being moved accidentally upward by a light spiral spring I around the tube D, the lower part of the spring I, resting or bearing upon the upper part of the collar or 55 socket E, and the upper part against a shoulder s, on the tube as seen in Fig. 2. When the parts are in this position as shown in Fig. 2, the needle may be termed "cocked" and it will be seen that if the hub 60 or cylinder G were forced upward the triangular pins m, m, would force apart the plates n, n, and the needle would be forced upward and strike against the cap on the nipple c, by the action of the spiral spring j.

A small nut u, is placed upon the lower end 65 of the needle E, merely to prevent the separation of the hub G, and tube D, when the needle is not "cocked", this nut is not indispensable but is convenient and keeps the parts above named together. This being 70 understood the whole operation may be briefly stated:

The needle is first cocked within the tube D, as just described and the implement is 75 gently lowered into the ocean until the surface of the water is at the upper parts of the spiral flanches a, a; the implement is then dropped or let fall and the spiral flanches a, a, will cause the implement to rotate as it descends, thus insuring a vertical line of descent. The hub or cylinder G of course first touches the bottom and the impetus or inertia of the implement will overcome the resistance of the spiral spring I around the tube D, and the tube D with 80 the needle and plates n, n, at its lower end, will be forced downward and the triangular pins m, m, will force apart the plates n, n; the needle will consequently be liberated and the spring j, will force the needle 85 against the cap on the nipple, exploding the cap and igniting the powder in the chamber B, which will burst or explode. The sound of the explosion will be heard or the concussion will be felt at the surface 90 of the ocean, and the exact time which elapses from the letting fall of the implement till the explosion is heard must be ascertained by a stop watch. By this means 95 the exact depth of the ocean may be ascertained, for a table may be formed by experiment, the depth being in proportion to the time which elapses from the letting fall of the implement till the explosion is heard or the concussion of the water felt.

100 The implement is intended to be made of various sizes; for great depths large chambers would be required to hold sufficient powder to enable the report to be heard or the concussion to be felt sensibly.

105 From the above description it will be seen that the ordinary percussion cap may be used on the nipple c.

The powder may also be ignited by employing a small pill of an alloy of potassium, which may be put within the nipple c, the nipple being covered with an empty cap of sufficient strength to resist the pressure of the water. The upper part of the needle may be pointed so as to rupture or 115 pierce the cap when the needle is liberated and then the water would come in contact with the alloy of potassium and ignition would instantly follow. I would give the 120 preference to the employment of the alloy 125 of potassium over the percussion cap, as the alloy of potassium requires the presence of water to cause ignition and the accidents

which might ensue from the casual liberation of the needle in using percussion caps would be thereby avoided.

In case of potassium being used for ignition, small apertures t , may be made in the upper part of the tube D, for the ready admission of water.

Thus the depth of the ocean may be sounded with the greatest facility and the strength and locality of current may also be ascertained, for if the ocean is agitated at any distance from the spot where the implement was dropped or let fall, that distance would

indicate a current and its strength; the strength or rapidity being in proportion to the distance. 15

Having thus described my invention, what I claim as new, and desire to secure by Letters Patent, is:

An implement constructed and operated 20 substantially as herein described, for the purpose of sounding the depth of the ocean.

CHARLES F. BROWN.
